UNITED STATES PATENT OFFICE.

JOSEPH J. GOELLNER, OF ST. LOUIS, MISSOURI, ASSIGNOR TO LANDIS MACHINE COMPANY, OF ST. LOUIS, MISSOURI, A CORPORATION OF MISSOURI.

PRESSER CONTROL FOR SEWING MACHINES.

1,212,761.

Specification of Letters Patent. Patented Jan. 16, 1917.

Application filed August 10, 1916. Serial No. 114,911.

To all whom it may concern:

Be it known that I, JOSEPH J. GOELLNER, a citizen of the United States, residing at the city of St. Louis, State of Missouri, have 5 invented a certain new and useful Improvement in Presser Control for Sewing-Machines, of which the following is a full, clear, and exact description, such as will enable others skilled in the art to which it appertains to make and use the same, reference being had to the accompanying drawings, forming part of this specification.

This invention relates to an improvement in the presser foot operating mechanism 15 of a leather sewing machine of the type commonly designated the Goodyear machine, and which is disclosed in United States Letters Patent No. 473,870 of April 26, 1892.

20 The object of the invention is to provide an arrangement whereby the presser foot may be automatically released to engage the work immediately upon the starting of the machine, so that both hands of the operator may be left free to hold the work in position.

By reference to the accompanying drawings—in which Figure 1 is a side elevation of the device, Fig. 2, a side view of parts in 30 shifted positions—it will be understood that the numeral 1 designates generally the frame of the machine, in which is mounted the customary operating shaft carrying a cam 2. The presser foot which is designated 4 is 35 pivotally mounted at 4^a in the customary fashion so that it may be swung upwardly and downwardly into coöperation with the work which is supported on the work-support 5. A handle 6 is provided whereby 40 the presser foot may be swung away from the work-support 5 to release the work. The rear end of the presser foot is pivotally connected to a frame member 7 which forms a mounting for the measuring mechanism 45 of the thread throw-off, and said frame 7 is movable vertically by the rocking of the presser foot 4. A spring 8 coöperates with the frame member 7 to urge it upwardly. In a movable block mounted in the bifurcated lower portion of frame member 7 is 50 pivoted an oscillating link 9 connected at its upper end to a connecting rod 10 which is reciprocated by the movement of a bell-crank 11 to which movement is imparted

by the cam 2. These are all well known parts of the thread measuring mechanism, so that it will be readily understood that upon the starting of the machine, cam 2 will be rotated to reciprocate rod 10, as is permitted by the pivotal connection through link 9 and the space between the divergent arms of frame member 7.

On the retaining plate 12 of the feed slide, I mount an upstanding flat spring member 14 having a rearwardly projecting portion 14^a and an upwardly extending terminal portion 14^b. The rearwardly or horizontally extending portion 14^a is adapted to fit over a shoulder 15 carried on the frame member 7, when said frame member is in its lowered position which it occupies when the presser foot 4 is swung away from the work-support 5. This shoulder may be formed integrally on the frame member 7, or it may be provided in the form of a pin, lug, or screw suitably seated in the said frame member. When the spring retaining member 14 is in engagement with the shoulder portion 15, it holds the frame member 7 in its lowered position, and as a consequence holds 80 the presser foot in its raised position. In this position, the operator may utilize both hands to insert the work between the presser foot and the work-support. When ready to start the machine, the operator presses the clutch pedal with his foot, which starts the machine in the well known fashion by throwing the driving mechanism into engagement with the operating shaft. Immediately, upon the starting of the shaft, the 85 cam 2 is rotated to rock bell crank 11 and thrust the connecting rod 10 forwardly. When this occurs, the forward end of rod 10 comes into contact with the terminal portion 14^b of the spring retaining member 90 and forces the spring forwardly to such an extent that it is removed from over the shoulder 15. There being nothing further to retain the frame 7 in its lowered position, it is immediately raised by action of spring 100 8, and presser foot 4 moved into operative engagement with the work on the work-support 5.

By means of this arrangement, it will be obvious that the operator is relieved from 105 the necessity of manually operating the presser foot to insert the work, and thereby is left with both hands free to properly

manipulate the work and hold the parts in proper relative position while he is inserting it into the machine.

What I claim is:

5 1. In combination with the presser foot and attached thread measure frame, of a resilient retaining member adapted to engage the frame and retain it in its lowered position, and a reciprocating member movable during operation of the machine and adapted to engage the retaining member to release the measure frame.

10 2. In a sewing machine in combination with the presser foot and the thread measure frame shiftable therewith, of a resiliently operating retaining member arranged to engage the frame when the presser foot

is raised, and having a portion engageable by the thread throw-off mechanism to release said frame and permit the movement of the 21 presser foot to operative position.

15 3. In a sewing machine in combination with the presser foot, the thread-measuring frame movable therewith, and the throw-off mechanism mounted on said frame, of 25 a retaining member mounted on a stationary portion of a machine and arranged to retain the presser foot in raised position, said retaining member having a portion operable by the throw-off mechanism to release the 30 presser foot.

In testimony whereof I hereunto affix my signature this 7th day of August, 1916.

JOS. J. GOELLNER.
